UNITED STATES PATENT OFFICE.

ELMER E. PALMER, OF SYRACUSE, NEW YORK.

URINAL.

947,082.

Specification of Letters Patent. Patented Jan. 18, 1910.

Application filed January 29, 1908. Serial No. 413,194.

To all whom it may concern:

Be it known that I, ELMER E. PALMER, of Syracuse, in the county of Onondaga, in the State of New York, have invented new and useful Improvements in Urinals, of which the following, taken in connection with the accompanying drawings, is a full, clear, and exact description.

This invention relates to certain improvements in urinals of the open stall type adapted to be used in public buildings, depots and other places where such fixtures or apparatus may be convenient. The difficulty in maintaining these public urinals and environments in a perfectly sanitary and odorless condition is universally recognized and in most instances this is attributable to imperfect drainage, improper ventilation or to the use of unsuitable material and loose manner of assembling the parts.

My object, therefore, is to entirely remove these objectionable features by constructing the entire system of stalls and drainage conduits of slate or equivalent non-absorbent with as few joints as possible, and by providing the stalls with lower and upper ventilating ports which communicate by indirect passage with a main ventilating flue.

Another object of equal importance is to locate the flush pipe in a horizontal plane between the lower and upper ports so as to constantly discharge the water downwardly against the back or impact plates which in turn conduct the excretion and water to an underlying inclined trough, the latter communicating at its low point with a suitable sewer pipe.

The displacement of air by the continuous downward discharge of water from the flush pipe naturally causes a rush of air against the back plates, part of which air is carried downwardly by the water current and escapes to the ventilating flue through the lower ventilating ports but the greater part of such air is brought into a whirl or eddy moving against the back plates and unless some provision is made for the breaking up or disintegration of this eddy, the same air will continue its whirling motion in substantially the same place and soon become vitiated thereby rendering the air with which it comes in contact foul and odorous and cause the entire air throughout the

room to become permeated with the same foul odors.

The object, therefore, in providing ventilating ports above and beneath the flush pipe or rather in locating the flush pipe between the lower and upper ventilating ports and connecting said ports to the main ventilating flue in which a continuous up-draft is maintained, is to break up or disintegrate the eddying currents of air which may tend to accumulate in proximity to the back or impact plate.

Other objects and uses relating to specific parts of the system will be brought out in the following description.

In the drawings—Figure 1 is a perspective view of a multiple urinal system embodying the various features of my invention but omitting the main ventilating flue. Fig. 2 is a transverse sectional view through the apparatus seen in Fig. 1. Fig. 3 is a longitudinal vertical sectional view through the several stalls and underlying slab in which the drain trough is formed.

In carrying out the objects stated I first construct a suitable foundation —1— of masonry of any approved construction and of sufficient length to receive and support a continuous superposed slab —2— of slate or equivalent non-absorbent material having its upper face provided with a lengthwise channel —3— terminating near the ends of the slab and having its bottom inclined from one end to the other, said channel communicating at its low end with a suitable soil pipe —4—, the latter being adapted to be connected to a sewer or other drainage conduit, not shown. This slab is usually coextensive in length with that of the combined stalls presently described and upon the front edge of the slab —2— at the front side of the trough —3— is placed a series of spacing blocks —5— also of slate which are spaced a uniform distance apart corresponding to and directly under the partitions or sides of the stalls and serve to support the rear edge of a superposed slab —6— of slate, this latter slab being continuous from end to end and of a length substantially coextensive with that of the combined stalls, said slab —6— being of considerably greater width than the underlying slab —2— and has its front edge projecting across a ventilating space —7— as best seen in Fig. 2 and

supported upon the upper edge of a suitable foundation —8— and in this particular instance is embedded in a concrete floor —9— forming the top of the foundation —8. The ventilating space —7— is, therefore, enclosed by the foundations —1— and —8— and coping —6—, the rear foundation —1— being provided with a ventilating passage —10— which connects the ventilating space —7— with a main ventilating flue —11—.

The spacing blocks —5— serve the purpose of supporting the rear edge of the coping or floor slab —6— some distance above the upper face of the trough slab —2— leaving intervening ventilating spaces —12— between the spacing blocks and also between the trough slab —2— and floor slab —6—, which connect the ventilating spaces —7— with the lower portions of the stalls herein-after described.

The floor slab —6— is made in one piece and laid on a slight incline transversely from front to rear with its rear edge extending a short distance beyond the spacing blocks —5— and front edge of the trough slab —2— and terminates directly over the trough or chamber —3— so any accumulations of moisture upon the upper surface of the floor slab —6— will readily flow rearwardly and downwardly from the rear edge of the slab —6— into the underlying trough —3— where such moisture will readily flow along the inclined bottom —3— into the soil pipe —4—.

The urinal proper consists in this instance of a series of stalls each comprising back plates —13— and sides —14—, which are capped by a suitable coping or top plate —15— all of which latter parts are made of slate.

The back piece —13— which may be made in a continuous slab of slate is disposed in a vertically inclined plane with its lower edge seated in a groove —16— upon the upper face of the trough slab —1— which is at the rear of the trough —3— where it is cemented or otherwise secured in place, the upper edge of said back piece abutting against and secured to the under side of the top plate —15— and is provided with a series of ventilating ports —18— one for each stall, said ventilating ports —18— being formed by cutting away portions of the upper edge of the plates —13— between the side pieces —14—.

The intermediate side pieces —14— are disposed in parallel vertical planes uniform distances apart with their lower edges resting upon and secured to the upper face of the floor plate —6— directly over and in vertical alignment with the spacing blocks —5— while the side pieces at the ends are similarly disposed but have their lower edges resting upon the upper faces of the end

spacing blocks —5— between the end of the floor plate —6— and outside concrete floor —9—, the upper edges of said pieces all terminating against the under side of the top plate —15—.

The rear edges of the side pieces —14— follow the upward incline of and are secured to the back piece —13— against which they abut while the front edges are preferably disposed in vertical planes so that each side piece —14— extends forwardly from the back piece over and in front of the underlying groove or channel —3— and are of sufficient transverse width from front to rear to practically conceal the occupant of the stall.

The lower rear edges of the intermediate partitions or side pieces —14— are cut away forming ventilating ports —19— connecting the several stalls and communicating with the trough —3— through suitable passages —20— which are formed between the rear edge of the floor slab —6— and front face of the adjacent portion of the back piece —13— and which latter cause the excretions and water to flow downward from the back piece —13— into the trough —3— and also allows the vitiated air to escape through the ventilating spaces —12— into the chamber —7— and thence through the passage —10— into the main ventilating flue —11—.

It is now clear that each stall is provided at its lower side with ventilating ports —19— and —20— for removing the downwardly flowing currents of air, while the upper portion of the stall is similarly provided with a ventilating port —18— for permitting the escape of the upwardly flowing vitiated air or gases thereby taking care of all foul air and gases which may tend to accumulate in the stall.

In order that the back piece —13— which constitutes the impact plate of each stall may be thoroughly and continually cleansed from excretions, I provide a flush pipe —21— which is common to all of the stalls and is located in a horizontal plane between the lower ports —19— and upper ports —18— and directly in front of the back plate —13—, said flush pipe being provided in its lower side with fine apertures —22— through which jets of water are discharged continuously and downwardly against the front faces of the back impact plates of each stall striking said back plate which is above the point where the excretions are more liable to accumulate thereby keeping the impact plates entirely free from such accumulations and depositing the same into the underlying trough —3— where they are immediately carried away to the soil pipe —4—.

The back piece —13— constituting the impact plates of the several stalls is located

some distance in front of the adjacent side of the main ventilating flue —11— leaving an intervening space —25— extending from the top plate —15— downwardly at the rear 5 of the trough slab —1— and communicating at its lower end with the passage —10— and main flue —11—, the lower end of the short side of said main flue being provided with a passage —26— connecting the lower 10 end of the ventilating space —12— with the interior of said flue.

The top plate —15— which rests upon the upper edges of the back piece —13— and side pieces —14— extends some distance forwardly and upwardly beyond the back piece —13— and its rear edge is preferably embedded in the adjacent wall of the main flue —11— so as to firmly hold it in place, and form a substantially air tight 20 joint with the flue as well as with the upper edges of the back and sides of the stalls.

The main water supply pipe as —27— which supplies water to the flush pipe —21— preferably extends downwardly through an 25 aperture in the top plate —15— close to the front wall of the flue —11— and into the upper portion of the space —25— where it is offset laterally through an aperture in the back —13— and connected to the flush pipe 30 —21—, said supply pipe being provided with a suitable valve —28— to regulate the discharge of water from said flush pipe.

It is desirable to provide some means for creating an up-draft of air through the ventilating flue —11— and for this purpose I have located in the lower portion of the flue 35 a suitable heater —28— which reduces the specific gravity of the air and causes it to rise more or less rapidly through the flue 40 thereby drawing the vitiated air from the chamber —7— and ventilating spaces —25— to which such vitiated air readily escapes from the room in which the stalls are located through the lower ports —19— 45 and 20 and upper ports —18—.

The downward discharge of water from the flush pipe against the impact plates causes more or less down draft of the vitiated air in the immediate vicinity of the 50 stalls, said vitiated air finding exit through the ports —19— and —20— and —12— to the chamber —7— and thence to the ventilating flues through the passages —10— and —26— but this action of the water 55 tends to produce a circular motion of the air some distance above the bottom within the center of the whirl or eddy in the vicinity of the discharging water so that unless some provision is made for breaking up or 60 disintegrating these eddying currents they will continue to revolve or whirl in the upper portions of the stalls and soon render the whole atmosphere of the room more or less foul, and in order to overcome this, I 65 have provided ventilating ports —18—

which are above the flush pipe —21— in line with the backwardly moving currents of air so that the air which rushes rearwardly against the back plates finds ready exit through the ports —18— thus breaking 70 up or disintegrating the tendency toward eddying currents and causing the vitiated air in the upper portions of the stalls to readily escape through the ports —18— and into the ventilating space —25— and thence 75 into the ventilating flue —1— which extends some distance to the exterior of the building.

It will be seen from the foregoing description that the principal features of my invention are:—1st the construction and relative arrangement of the trough and floor slabs together with the intervening spacing blocks and ventilating ports, and 2nd, the relative arrangement of the flushing pipe between the lower and upper ventilating 80 ports of the several stalls whereby a part of the foul air is carried off through the bottom ports and aided by the down rush of water while the tendency of the air to form into eddys or whirls in the upper part 85 of the stall is obviated by the upper ports which operate to split up or disintegrate these eddying currents of air which are more or less vitiated and to convey such vitiated air from the upper portions of the 90 stall to the main ventilating flue, the lower and upper ventilating passage of the several stalls communicating by indirect passages 95 with a single opening in the front side of the main ventilating flue and by heating the 100 air in said flue it is clearly evident that a strong upward draft therein is continually maintained tending to augment the withdrawal of foul air or gases from the stalls into said flue.

105 What I claim is:

1. In a urinal system, the combination of a slab having a lengthwise trough in its upper side, the bottom of which trough is inclined from one end toward its opposite end, 110 a discharge pipe communicating with the low end of said trough, a series of spacing blocks mounted upon the upper edge of said slab at one side of the trough and spaced some distance apart forming intervening 115 ventilating passages, a floor slab having one edge resting upon the upper faces of said spacing blocks and inclined transversely toward the underlying trough slab, the rear edge of said floor slab terminating directly 120 over the trough, a support for the floor slab and forming in connection with the trough and floor slabs a ventilating space with which said passages communicate, a back piece having its lower edge resting upon the 125 upper face of the trough slab at the rear side of the trough, and side pieces having their lower ends resting upon the upper face of the floor slab directly over said spacing blocks and their rear edges secured to the 130

back piece leaving an intervening ventilating passage between the back piece and rear edge of the floor slab, a flushing pipe discharging against the back piece, said back piece having ventilating ports above the flush pipe to break up and carry off eddying currents of air which may tend to accumulate in the vicinity of the flush pipe.

2. A urinal system comprising a slate slab having a lengthwise trough in its upper side, the bottom of said trough inclining lengthwise from one end toward the passage end, a discharge pipe communicating with the low end of said trough, a series of spacing blocks of the same material seated upon the upper face of the trough slab and spaced some distance apart to provide ventilating spaces, a floor slab of slate having its rear edge resting upon the upper faces of said spacing blocks and terminating directly over said trough, a support for the floor slab and forming in connection with the trough and floor slab a ventilating space with which said ventilating passage is communicated,

an upwardly and rearwardly inclined back piece having its lower end resting upon the upper side of the trough slab at the rear of said trough some distance from the rear edge of the floor slab leaving an intervening ventilating space communicating with the spaces between said blocks, upright side pieces having their lower edges resting upon the top face of the floor slab and provided with ventilating ports communicating with the ventilating spaces between the floor slab and back piece said back piece having its upper edge provided with a ventilating port, a main ventilating flue communicating with said ventilating ports, and a flush pipe located in the horizontal plane between the upper and lower ventilating ports.

In witness whereof I have hereunto set my hand this 22 day of January 1908.

ELMER E. PALMER.
